UNITED STATES PATENT OFFICE.

ISAAC H. TRABUE, OF LOUISVILLE, KENTUCKY.

CAR-COUPING.

SPECIFICATION forming part of Letters Patent No. 295,956, dated April 1, 1884.

Application filed July 3, 1883. (No model.)

To all whom it may concern:

Be it known that I, ISAAC H. TRABUE, a citizen of the United States, residing at Louisville, in the county of Jefferson and State of Kentucky, have invented certain new and useful Improvements in Car-Couplers; and I do hereby declare the following to be a full, clear, and exact description of the invention, such as will enable others skilled in the art to 10 which it appertains to make and use the same.

My invention relates to that class of car-couplers which are provided with a pin-supporting catch, which releases the pin and permits it to fall when the link enters the draw-head.

15 The object of my invention is to provide a catch that will automatically return to its place when the link and pin are withdrawn from the bend.

20 The nature of my invention consists of constructions and combinations, all as will hereinafter be described and claimed, reference being had to the accompanying drawings, in which—

25 Figure 1 represents a longitudinal section through two draw-heads, one having the link secured therein and the other ready to receive the link; Fig. 2, a detail showing the pendulum.

30 A A' represent the draw-heads, B the link, and C C' the pins. The draw-heads are each provided with an upper and lower pin-hole, a a', similar to those in use, and a bolt-hole, a', back of the upper pin-hole. This hole a' 35 may be vertical or oblique, and round, square, or any other form in cross-section. Through this opening is inserted a bolt, D, screw-threaded at its upper end, d, and to its lower end is pivoted in any suitable manner a swing- 40 ing or pendulum catch, E. As shown in the drawings, the catch is attached to the bolt by means of a pintle, e.

The pendulum E may be of any desired form, and should be provided with a catch, e', 45 and weighted at its lower end, e''. This end

should be weighted sufficiently to support the pin in the hole a preparatory to its fall through the lower hole, a'; to catch the link, which, when it strikes the pendulum E, forces the latter back and frees the catch e' from the pin. 50

In the draw-head A' the link is shown held therein by the pin. The weighted part of the pendulum rests against the upper side of the link, which is thereby held in such a position that it can readily pass into the draw-head A 55 and release the pin, which will lock the coupling. If desired, the draw-heads may be recessed at e, so that the pendulum may have greater swing when the link is pushed into the draw-head. 60

The preferable mode of placing the pendulum in place is to attach it to the bolt and pass the latter upwardly through the opening a' and hold it in place by means of the nut F, which is screwed upon the end d; or the bolt 65 may be passed through the hole a' and the pendulum attached thereto within the draw-head.

It is obvious that this device may be attached to any of the draw-heads now in use by simply 70 drilling the hole a' in the upper part thereof.

What I claim as new is—

1. In a car-coupler, the combination of a head having pin-holes and a bolt-hole, a pin, and a catch suspended from said draw-head 75 by a bolt passing through the bolt-hole in the draw-head.

2. In a car-coupler, the combination of a head having pin-holes and a bolt-hole provided with a recess, c, a pin, and a catch suspended from said draw-head by a bolt passing through the bolt-hole in the draw-head, substantially as described. 80

In testimony whereof I affix my signature in presence of two witnesses.

ISAAC H. TRABUE.
